UNITED STATES PATENT OFFICE

PAUL A. GOLLNICK, OF CHICAGO, ILLINOIS, ASSIGNOR TO SELECTOGRAPH COMPANY, OF CHICAGO, ILLINOIS, A CORPORATION OF ILLINOIS

METHOD OF TREATING PAPER

Original application filed June 15, 1928, Serial No. 285,747. Divided and this application filed September 12, 1929. Serial No. 392,113.

This application is a division of one filed June 15, 1928, Serial No. 285,747.

The main objects of this invention are to provide an improved method of coating porous sheet material; and to provide an improved method of impregnating Japanese yoshino paper with a liquid in the manufacture of stencil sheets.

An illustrative embodiment of the means for carrying out this improved process is shown in the accompanying drawings, wherein:

Figure 1 is a top plan of an improved coating tank showing a sheet floating on the surface of the bath.

Fig. 2 is a side elevation of the same.

Fig. 3 is a section taken on the line 3-3 of Figure 1, the dotted outline representing the raised position of the contact element.

Fig. 4 is a longitudinal section of the tank taken on the line 4-4 of Fig. 1, the dotted outline representing the position of the sheet as it is withdrawn through the wiping mechanism.

Stencil sheets for use in connection with addressing machines and analogous printing devices are generally made of porous sheet material, such as Japanese yoshino paper, impregnated with a substance impervious to ink to form a coating in which the stencil characters are cut to permit the ink to print through the fibers of the paper.

Heretofore, in the manufacture of stencil sheets, the coating has been applied to the sheet by a brush or spraying device or by immersing the entire sheet in a bath. Scrapers have also been used for wiping the surplus liquid from the coated side or sides of the sheet, but the scrapers of prior devices were not employed for effecting a penetration of the liquid into the paper.

Applying the coating to the sheets by the spraying or brushing process is objectionable because of the time consumed and the difficulty in handling the sheets during the appli-

cation of the liquid. The dipping process is objectionable because of the flimsy character of the yoshino paper.

If Japanese yoshino paper is floated on a liquid bath for coating the lower surface of the sheet, the liquid will in time penetrate the sheet so as to coat the upper side also. However, when thus coated, the sheet is unsatisfactory because the coating is not uniform on both sides of the sheet and does not properly bind the fibers of the paper. Stencils coated in that manner make impressions having what is known in the trade as a "feather edge". The letters and numerals which are printed from those stencils are ragged and not clearly defined.

The aforementioned objections to processes heretofore in use are cured by this improved process which consists in applying a liquid to only one side of the sheet and then applying a contact element to the other side thereof to rupture the surface tension of the liquid, thereby causing the liquid to penetrate the sheet for coating the opposite side thereof.

In carrying out this improved process, the liquid film is applied to only one side of the yoshino paper, preferably by floating the sheet on the surface of a bath of the liquid and then, as the sheet is being withdrawn from the bath, applying a contact element to the upper surface thereof.

In the form shown, the means for carrying out this improved process comprises a tank 1, adapted to contain a bath 2 of the liquid for treating porous sheets 3, and having a wiping mechanism 4 adjacent one end thereof, through which the sheets are drawn after being floated on the surface of the bath.

The tank 1 may be made of any suitable size and shape and is seated in a water jacket 5, through which warm water flows for keeping the bath at a certain temperature. The jacket 5 has an inlet conduit 6 and a drain 7.

In the construction illustrated, the wiping mechanism 4 comprises a pair of stationary

supporting rods 8 and 9 and a movable contact element 10.

The rod 8 is rigidly secured to the side walls of the tank 1 and the rod 9 is rigidly mounted on a pair of brackets 11 secured to respectively opposite sides of the tank 1 adjacent the rod 8.

The rods 8 and 9 span the tank 1 and are disposed in spaced relation to each other to form a support, over which the lower film coated surface of the sheet is wiped as the sheet is withdrawn from the bath.

The rods 8 and 9 are arched toward the opposite end of the tank, so as to spread each sheet to smooth out the wrinkles as the sheet is wiped over the rods.

The contact element 10 comprises a rod having a mounting 12, which is pivotally secured to an arm 13 formed on one of the brackets 11, so as to permit the contact element to move into notches 14 formed in the brackets 11 for engaging the top surface of a sheet supported on the rods 8 and 9.

Mounted on the outer end of the rod 10, 25 is a counterweight 15, which normally holds the free end of the rod in its raised or open position. The rod 10 is also arched, so as to conform to the rods 8 and 9.

In operation, a sheet 3 is secured at one 30 end to a suitable clamp 16, which is held in one hand of the operator. The sheet is then placed on the surface of the bath, so that the lower surface of the sheet becomes coated with a film of the liquid. The sheet is then 35 drawn edgewise and the forward end thereof is lifted out of the bath and placed over the rods 8 and 9.

The rod 10 is then lowered into the recesses 40 14, so as to contact with the upper surface of the sheet and, while the rod 10 is held in its lowered position, the sheet is wiped through the rods. The lower rods 8 and 9 remove the surplus liquid from the lower surface of the sheet and the contact rod 10 45 breaks the surface tension of the film, thereby causing the liquid to penetrate the sheet for uniformly coating the top surface thereof.

A sheet which is coated with this improved 50 method is very satisfactory for stencil purposes because the fibers are firmly bound by the uniform coating on both sides of the sheet.

It is to be understood that numerous details of the construction shown and steps in the process described may be varied without departing from the spirit of this invention as defined by the following claims:—

I claim:

60 1. The method of coating a porous sheet of Japanese yoshino paper in the manufacture of stencils which consists in applying a liquid to only one side of the sheet, and then wiping the other side thereof for breaking the surface tension of the liquid and thereby

causing the liquid to penetrate the sheet for coating the opposite side thereof.

2. The method of coating a porous sheet of Japanese yoshino paper for use in making stencils which consists in placing the sheet on the surface of a liquid bath to apply a liquid film to only one side of the sheet, and then removing the sheet from the bath and simultaneously wiping the other side thereof for breaking the surface tension of the liquid and thereby causing the liquid to penetrate the sheet for coating the opposite side thereof.

Signed at Chicago this 9th day of Sept., 1929.

PAUL A. GOLNICK.
